(57) **CLAIM**

The ornamental design for an electronic thermometer with wireless communication device, as shown.

DESCRIPTION

FIG. 1 is a front, top, and right side perspective view of an electronic thermometer with wireless communication device showing our new design;

FIG. 2 is a rear, bottom, and left side perspective view thereof; FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front, top, and right side perspective view showing a condition in which a cover is removed thereof;

FIG. 10 is a rear, bottom, and left side perspective view showing a condition in which the cover is removed thereof;

FIG. 11 is a front view showing a condition in which the cover is removed thereof;

FIG. 12 is a rear view showing a condition in which the cover is removed thereof;

FIG. 13 is a bottom view showing a condition in which the cover is removed thereof;

FIG. 14 is a right side view showing a condition in which the cover is removed thereof;

FIG. 15 is a left side view showing a condition in which the cover is removed thereof;

FIG. 16 is a front, top, and right side perspective view of the removed cover thereof;

FIG. 17 is a front view of the removed cover thereof;

FIG. 18 is a rear view of the removed cover thereof;

FIG. 19 is a top view of the removed cover thereof;

FIG. 20 is a bottom view of the removed cover thereof;

FIG. 21 is a right side view of the removed cover thereof; and,

FIG. 22 is a left side view of the removed cover thereof.
